(57) **CLAIM**

I claim the ornamental design for the spinal fusion cage, as shown and described.

DESCRIPTION

FIG. 1 is a top, front perspective view of a spinal fusion cage according to an embodiment of the disclosure.

FIG. 2 is a top view of the spinal fusion cage, the opposite side being identical thereto.

FIG. 3 is a right view of the spinal fusion cage, the opposite side being identical thereto.

FIG. 4 is a front view of the spinal fusion cage; and,

FIG. 5 is a rear perspective view of the spinal fusion cage. The portions shown in dashed lines form no part of the claimed design.
